UNITED STATES PATENT OFFICE.

ARTHUR W. CARTWRIGHT, OF SOUTH EUCLID, OHIO, ASSIGNOR TO RICHARDSON CORPORATION, OF ROCHESTER, NEW YORK, A CORPORATION OF NEW YORK.

DISPENSING APPARATUS FOR CARBONATED BEVERAGES.

Application filed April 9, 1927. Serial No. 182,476.

This invention relates to dispensing apparatus for carbonated beverages, and has particular reference to the general type of apparatus illustrated in Humphrey Patent No. 5 1,546,733, July 21, 1925, and in the pending application of Harry J. McCue, Serial No. 173,167, filed March 5, 1927.

The purpose of the invention is to provide a simple and efficient valve control 10 mechanism in the general type of dispenser referred to, wherein beverage is drawn from both a liquefying chamber and direct from a source of high pressure supply, and a more specific object is to obtain the desired results 15 in such a way as to assure at all times a uniform proportioning between the liquefied or less highly carbonated, and more highly carbonated supplies so as to always serve a beverage of a standard degree of carbonation or effervescence.

Another purpose of the invention is to afford a structure such that the beverage is automatically sprayed into the top of an inverted transparent display container as 25 the beverage is drawn for serving, and also permitting a continuous spray discharge into the transparent container at times when the beverage is not being drawn, if this is desired.

30 An additional purpose of the invention is to afford simple and efficient means for obtaining a predetermined variation or adjustment of the supply of beverage coming from the liquefying chamber in case it is desired to effect a change of proportions between the high pressure supply which is 35 constant and the supply from the liquefying chamber which is variable, but which when once set always gives the same proportions 40 as the drink is served.

Still a further object of the invention is to afford a construction that permits the high pressure supply, when its control valve is opened, to travel both to the top of the 45 transparent display container, where it is discharged against the sides thereof, and also into the outlet valve housing which communicates with the beverage supply in the liquefying chamber, thus causing a certain amount of the more highly carbonated 50 beverage to be discharged directly into the body of the liquid in the bottom of the liquefying chamber, thereby enlivening and keep-

ing the latter in a more agitated and effervescent state than otherwise.

To these and other ends, the invention consists in the construction and arrangement of parts that will appear clearly from the following description when read in conjunction with the accompanying drawings, 60 the novel features being pointed out in the claims following the specification.

In the drawings:

Figure 1 is a vertical sectional view, with parts in elevation, of a carbonated beverage 65 dispenser showing applied thereto a preferred embodiment of the present invention;

Figure 2 is a detail vertical sectional view on line 2—8 of Figure 1;

Figure 3 is an enlarged vertical sectional 70 view on line 3—3 of Figure 2;

Figure 4 is a detail vertical sectional view on line 4—4 of Figure 3, and

Figure 5 is a detail elevation with the 75 outlet valve housing removed.

The invention may be carried out in a number of different ways, and in order to illustrate one practical exemplification, it is disclosed in conjunction with a type of carbonated beverage dispenser including a 80 transparent display container into which the charged beverage can be sprayed, and an overflow pipe by which it can be returned to the source of supply and circulated when it is not drawn from the container as fast as 85 it enters, although it will be obvious that the invention can be applied in other ways than herein specifically set up.

In the structure referred to, there is a liquefying chamber which includes a receptacle 1 suitably mounted and attached on a base 2, and an inverted bowl-like display container 3 which is preferably transparent and rests upon a cover 4 which surmounts the receptacle 1 and also an outer receptacle 90 or container 5, a cooling chamber 6 being thereby afforded between the inner and outer receptacles 1 and 5.

The transparent display container 3 and cover 4 are held in fixed relation on the receptacles 1 and 5 through the instrumentality of a cap 7 which has threaded engagement with the upper end of a pipe 8, the latter being fixedly connected with a coupling 9 that in turn is fixedly united to a discharge 100 pipe 10, the carbonated drink being fed 105

through the pipe 10 and discharged in a spray through openings 11 in the coupling 9 against the side walls of the container 3, whence it flows down into the bottom of the chamber and is liquefied, being drawn off as desired through one or other of the discharge faucets that will be referred to presently.

The discharge pipe 10 leads to a high pressure casing 12 to which the beverage is supplied through a pipe 13 from a carbonator or other suitable source of high pressure supply, while 14 designates the overflow pipe carrying the surplus supply of beverage in the liquefying chamber back to the carbonator or other source of supply, thus maintaining a continuous circulation if a continuous spray into the container 3 is desired. 15 is a clean-out drain for the receptacle 1, and 16 and 17 designate inlet and outlet pipes for maintaining a continuous circulation of a cooling medium in the cooling chamber 6. A mechanism for controlling supply of the highly carbonated beverage to the top of the display container and for drawing off a drink of given proportions as between the direct supply from the high pressure supply and the supply from the liquefying chamber, will now be described in detail.

While Figure 1 illustrates two discharge faucets, one opposite the sides of the dispenser, both are connected with the high pressure casing 12 in the same manner and by similar valve mechanism, and it will therefore be necessary to show and describe only one of these, as in Figures 2 to 5 inclusive. Referring in detail to these particular figures, the high pressure casing 12 includes an inlet chamber 18 and a discharge passage 19. The latter is normally closed by the valve 20, mounted on the end of valve rod 21, which latter is movable in a sleeve 22 fixedly secured within the high pressure casing. The sleeve 22 has a series of ports 23 which permit the passage of liquid from the interior thereof upwardly to the discharge passage 19 when the valve 20 is opened, and under such conditions the high pressure supply of beverage can pass from pipe 13 through ports 23 to discharge passage 19, thence to discharge pipe 10 and out into the upper portion of the display container 3, whence it settles into the bottom of the receptacle 1 and is there liquefied or freed from more or less of its carbonic acid gas.

25 designates the outlet valve housing and 26 is the main outlet valve which is opened to permit drawing off the beverage for serving a drink, said valve being actuated by an operating device in the form of a handle 27 and an extension or arm 28 that engages a recess 29 in the valve rod 30 that carries the valve 26. The arm 28 has a slight play or

lost motion in the recess 29 for a purpose that will appear presently. The valve housing 25 is secured by a sleeve 31 on to a shoulder 32 of a fitting 33 that extends into the dispenser through the receptacles 1 and 5 in the manner shown in Figure 3, and is held by suitable nuts 34. The supply of liquefied beverage in the bottom of the container ordinarily covers the fitting 33, filling the space between said fitting and the high pressure casing 12, and flowing thence into the valve housing 25 already described, where its further travel is checked by the valve 26. It is desirable to provide means for varying the supply or amount of beverage from the liquefying chamber in proportion to the more highly carbonated supply, and to accomplish this, fitting 33 includes a wall or partition 35 having a series of openings 36, each being adapted to receive a threaded plug and by securing one or more of such plugs in said openings, it is possible to modify the amount of beverage drawn from the liquefying chamber, and to obtain just the desired proportioning or mixing between the more highly and less highly carbonated components of a drink. The more highly carbonated supply passes to the outlet valve housing 25 around the valve rod 21 already mentioned, and also around a collar 37 that is movable with the valve rod in the sleeve 22, the amount of beverage thus supplied being dependent on the amount of spacing between the collar 37 and the surrounding sleeve 22. 38 is a spring located between collar 37 and a shoulder 39 on sleeve 22 and acting to hold the valve 20 normally in closed position, while 40 is a stop secured to the end of the valve rod 21 and acting to hold the collar 37 in place thereon. 41 is a spring acting normally to hold the outlet valve 26 closed.

With the parts in the position shown in Figure 3, when it is desired to deliver a drink, the handle 27 is pulled forwardly or to the left with reference to said figure, and acts initially to move stop 40 inwardly and with it the valve 20, opening the latter. The more highly carbonated beverage supply then passes to the top of the display container through ports 23, passage 19 and pipe 10 as already described, and also a part of said highly carbonated supply passes longitudinally around the valve rod 21 and between it and the sleeve 22 and thence around the collar 37 into the outlet valve housing 25, whence it can return through openings 36 into the supply of liquefied beverage in the bottom of the container to enliven the same. Further movement of the handle 27 causes the arm 28 to move the valve rod 30 endwise, opening the outlet valve 26 and thus permitting drawing off a supply of beverage which always contains a predetermined proportion between the supply from the liquefy-

ing chamber and the supply from the high pressure chamber 18. If at any time it is desired to effect a continuous circulation of the beverage for display purposes within the container 3, while keeping the outlet valve 26 closed, the handle 27 is moved only far enough to open the valve 20 and can be held in such position by a movable stop 42 having an adjustable post 43 thereon that engages 10 the abutment 44 on the valve operating handle.

While the invention is herein described with reference to a particular structure and arrangement, it is not limited to the details herein disclosed, and this application is intended to cover any modifications or changes coming within the purposes of the improvement or the scope of the following claims.

I claim:

20 1. A dispensing apparatus for carbonated beverages comprising a liquefying chamber, an outlet valve, an outlet housing for said outlet valve having communication with the liquefying chamber, a high pressure casing, 25 an inlet pipe leading to the high pressure casing, a discharge pipe leading from the high pressure casing to the top of the liquefying chamber, and a high pressure valve normally closing communication between the 30 high pressure casing and the discharge pipe and operable automatically in advance of the outlet valve to permit passage of liquid from the high pressure casing to the discharge pipe.

25 2. A dispensing apparatus for carbonated beverages comprising a liquefying chamber, an outlet valve, an outlet housing for said outlet valve, a wall separating the outlet housing from the liquefying chamber and 40 having a series of openings therein, closures for said openings permitting predetermined adjustment of the volume of liquid passing from the liquefying chamber to the outlet housing, a high pressure casing, an inlet pipe leading to the high pressure casing, a discharge pipe leading from the high pressure casing to the top of the liquefying chamber, and a high pressure valve normally closing communication between the high pressure casing and the discharge pipe and operable 45 automatically in advance of the outlet valve to permit passage of liquid from the high pressure casing to the discharge pipe.

3. A dispensing apparatus for carbonated beverages comprising a liquefying chamber, an outlet valve, an outlet housing for said outlet valve having communication with the liquefying chamber, a high pressure casing 55 having restricted communication with the outlet housing, an inlet pipe leading to the high pressure casing, a discharge pipe leading from the high pressure casing to the top of the liquefying chamber, and a high pressure valve normally closing communication 60 between the high pressure casing and the

discharge pipe and operable automatically in advance of the outlet valve to permit passage of liquid from the high pressure casing to the discharge pipe and to the outlet housing.

4. A dispensing apparatus for carbonated beverages comprising a liquefying chamber, an outlet valve, an outlet housing for said outlet valve, a wall separating the outlet housing from the liquefying chamber and 75 having a series of openings therein, closures for said openings permitting predetermined adjustment of the volume of liquid passing from the liquefying chamber to the outlet housing, a high pressure casing having restricted communication with the outlet housing, an inlet pipe leading to the high pressure casing, a discharge pipe leading from the high pressure casing to the top of the liquefying chamber, and a high pressure valve normally closing communication between the high pressure casing and the discharge pipe and operable automatically in advance of the outlet valve to permit passage of liquid from the high pressure casing 80 to the discharge pipe and to the outlet housing.

5. A dispensing apparatus for carbonated beverages comprising a liquefying chamber, an outlet valve, an outlet housing for said outlet valve having communication with the liquefying chamber, an operating device for the valve, a source of high pressure supply, a normally closed valve controlling the high pressure supply and means controlled by 95 said operating device for opening both said valves in predetermined relation and drawing a beverage in predetermined proportions from the liquefying chamber and from the high pressure supply.

6. A dispensing apparatus for carbonated beverages comprising a liquefying chamber, an outlet valve, an outlet housing for said outlet valve having communication with the liquefying chamber, a high pressure casing 110 having restricted communication with the outlet housing, an inlet pipe leading to the high pressure casing, a discharge pipe leading from the high pressure casing to the top of the liquefying chamber, a high pressure valve controlling passage of liquid from the high pressure casing to the discharge pipe, and a valve operating device which when moved acts initially to open the high pressure valve and subsequently the outlet 115 valve, said operating device being positionable to hold the high pressure valve open and the outlet valve closed.

7. A dispensing apparatus for carbonated beverages comprising a liquefying chamber, 125 an outlet valve, an outlet housing for said outlet valve, a wall separating the outlet housing from the liquefying chamber and having a series of openings therein, closures for said openings permitting predetermined 130

adjustment of the volume of liquid passing from the liquefying chamber to the outlet housing, a high pressure casing having an inlet chamber and a discharge passage, inlet and discharge pipes communicating respectively therewith, a valve sleeve extending within the casing from the outlet housing to the inlet chamber and having ports permitting communication with the discharge passage, a high pressure valve movable endwise of said sleeve and normally closing its inner end to prevent movement of liquid from the

inlet chamber to the discharge pipe, a valve rod extending through said sleeve, said ports permitting passage of liquid from said inlet chamber to the discharge passage and also around the valve rod into the outlet housing when the high pressure valve is open, and an operating device which when moved acts initially to open the high pressure valve and thereafter the outlet valve.

In witness whereof, I have hereunto signed my name.

ARTHUR W. CARTWRIGHT.
